[57] CLAIM

The ornamental design for a liquid applicator, as shown and described.

DESCRIPTION

FIG. 1 is a top perspective view of a liquid applicator, showing my new design;

FIG. 2 is a bottom perspective view thereof;

FIG. 3 is a front elevational view thereof;

FIG. 4 is a side elevational view thereof;

FIG. 5 is a top plan view thereof;

FIG. 6 is a bottom plan view thereof.

The broken line disclosure in all views is for illustrative purposes only and forms no part of the claimed design.

FIG. 1.**FIG. 2.****FIG. 3.****FIG. 4.****FIG. 5.****FIG. 6.**
